FABRIC TRADE MARKING DEVICE

Filed Sept. 4, 1928

UNITED STATES PATENT OFFICE

ERIK GILBERT JEBSEN, OF KRISTIANSAND, NORWAY, ASSIGNOR TO CURTIS & MARBLE MACHINE COMPANY, OF WORCESTER, MASSACHUSETTS, A CORPORATION OF MASSACHUSETTS

FABRIC-TRADE-MARKING DEVICE

Application filed September 4, 1928. Serial No. 303,822.

This invention relates to an attachment designed particularly for the purposes of trade-marking cloth as it is being folded but capable of use for applying a stamp, brand, date, or design to any kind of textile material and adapted to be applied to various kinds of machines.

The principal objects of the invention are to provide for stamping or trade-marking the fabric while being folded or otherwise manipulated, thus saving one handling and reducing the labor cost; to provide for the application of the stamp or trade-mark while the cloth is without any progressive movement; to provide an arrangement by which the stamping or trade-marking will be performed at regular intervals, as for example a yard apart or half a yard, as may be desired, irrespective of any stretching of the fabric.

The invention is shown in the form of an attachment to a particular machine, but it is to be understood that a corresponding attachment can be applied to other machines and that the particular kind of folding machine illustrated is shown only to illustrate one method of employing the invention.

Other objects and advantages of the invention will appear hereinafter.

Reference is to be had to the accompanying drawings in which

Fig. 1 is a side view of a cloth folding machine with an attachment for trade-marking the cloth in accordance with this invention;

Fig. 2 is a plan of the attachment showing how the trade-mark can be applied;

Fig. 3 is an edge view of the same; and

Fig. 4 is a sectional view on the line 4—4 of Fig. 2.

It is the common practice in the textile industry to trade-mark the fabric or make any desired imprint upon it or a yardage mark as an entirely separate and distinct operation requiring the handling of the fabric especially for that purpose and putting it through a separate machine. During the various handling or packing processes the fabric is liable to become distorted in length on account of receiving different tensions on the several machines, or by varying atmospheric condi-

tions causing a difference in the length of the fabric by the contraction or elongation of the warp threads. This invention is designed to combine the folding and stamping in one machine, thus entirely eliminating one handling of the goods and even reducing the cost of the stamping part of the apparatus. Furthermore, the stamping is made during the final mechanical process at each fold of the finished fabric, thus giving a more accurate determination of the measurements of the fabric than would be obtained by previous practice, due to the different tensions just mentioned or varying atmospheric conditions.

For the purpose of illustrating the application of this invention, I have shown it as applied to a folding machine comprising a frame 10, a folding table 11, which, by means not shown in full, but comprising the mechanism 12, is raised and lowered at each operation in the ordinary manner. The mechanism 12 for operating the platform 11 is controlled from the main shaft 19 of the folding machine by a cam 8 and a lever 7.

This machine is provided with a guide 13 around which the fabric to be folded is drawn over tension rolls 14 and a delivery roll 15 and delivered to the folding head. This head is connected by a link 17 with an arm 18 mounted on the driving shaft 19 and rotating continuously. The head is also pivoted on a rod or frame 20 which is pivoted below. The head is pivotally connected by a blade rod 21 at the point 22 with a stationary frame 23. This head carries the folding blades 24.

The rotation of the arm 18 gives the head a definite path of motion across the folding table 11 on account of the pivots connected with the frame 20 and the rod 21 at 90 each forward stroke of the blades. It brings the folding blades 24 down under a jaw 25 at each side of the folding table as the blades 24 move across to that point. This clamp or jaw holds the fold down in the usual way 95 and the cloth is folded back and forth across the table while the table descends and rises to receive it and hold it. The operation of this folding machine has been described only in a sketchy manner because it is all old and 100

no invention is claimed in this folding machine.

On the guide 13 I locate a casing 30 in stationary position. This is so located that the fabric 9 passes under it as it moves along from the tension device 14 to the roll 15. The fabric is backed up underneath by this guide 13. The stamping, yardage, or trade-marking device may be of any desired character and I have shown one of well known form having a plunger 31 carrying an ink pad 32 and adapted to move down for the purpose of oscillating a printing head 33 from the position in contact with the ink pad shown in Fig. 4 to an exactly reverse position in which the inking head is in contact with the cloth 9, preferably on the selvage. This head is reversed by a couple of stationary pins 34 while the plunger and printing head move downwardly. The printing head is guided in a vertical slot 35 by means of a pin 36 projecting from the head.

It will be observed that the cloth is first drawn over the table 11 alternately by a forward stroke of the blades and repeated on the return stroke. Until the blades reach a point nearly over the center of the folding table, on the return stroke, the cloth remains stationary as it is folded and is gripped under one of the jaws 25.

It will be seen that the shaft 19 by the operation of the arm 18 fixed thereon controls absolutely the time at which this dwell of the cloth takes place. Consequently a cam 37 on this shaft is fixed in just the right position so that it will operate a lever 38 connected to operate the plunger 31 to depress it at just the time that the dwell takes place. As each dwell is governed by the length of the stroke of the folding blades, this impression will occur at regular intervals and will act as a determining factor in establishing the measurement of each fold.

Of course the attachment can be used as shown with one unit to mark or impress the cloth at each fold or two or more attachments can be used to sub-divide the distances between the dwells. Thus with the folding machine set to make a yard at each swing of the jaws, two stamping attachments can be placed on a guide eighteen inches apart, thus marking the fabric at each half yard.

By the application of the attachment or adjustment to a folding machine or other machine performing its usual functions in the usual way, the handling of the fabric to take it from such a folding machine and introduce it into a stamping or trade-mark machine is entirely eliminated. Furthermore, by co-ordinating the operation of the stamping device with the operation of the folding mechanism it is insured that the marks will be applied at equal distance apart on the fabric and they will mark the fabric with yard or half yard lengths. Thus the product is im-

proved and the cost reduced. The fabric in its folded condition is ready for the market and it is usual to determine by the number of folds the exact yardage measurement of the fabric, no other measuring system being used.

Although I have illustrated the invention as applied to a single type of machine and as employing a particular type of stamping device, I am aware of the fact that the invention can be carried out with other forms of either without departing from the scope of the invention as set forth in the claims.

Therefore, I do not wish to be limited in either respect, but what I do claim is:—

1. The combination with a fabric folding machine adapted to fold the fabric back and forth and leave the same amount of cloth in each fold, of a reciprocable printing attachment therefor connected with the mechanism for controlling the folding of the cloth and timed therewith to stamp the cloth once for each complete fold and at the same position in each fold.

2. The combination with a fabric folding machine having means for feeding the fabric intermittently of a stamping device mounted thereon and connected with the machine to apply a stamp to the selvage of the fabric when the passage of the fabric through the machine is interrupted to provide a slack or dwell and leave the cloth temporarily stationary.

3. The combination with a fabric handling machine comprising a main shaft having means thereon for controlling the operation of feeding and folding the fabric back and forth, of a stamping device on said machine, and means on said shaft for actuating said stamping device during that portion of the intermittent movement when the cloth is devoid of progressive motion.

In testimony whereof I have hereunto affixed my signature.

ERIK G. JEBSEN.
